UNITED STATES PATENT OFFICE.

JOSEPH GEORGE HUOT, OF MONTREAL, QUEBEC, CANADA.

CASEMENT-WINDOW ADJUSTER.

1,216,320.

Specification of Letters Patent. Patented Feb. 20, 1917.

Application filed April 22, 1916. Serial No. 92,814.

To all whom it may concern:

Be it known that I, JOSEPH GEORGE HUOT, a subject of the King of Great Britain, residing at Montreal, Province of Quebec, Canada, have invented certain new and useful Improvements in Casement-Window Adjusters, and I do hereby declare that the following is a full, clear, and exact description of the invention, such as will enable others skilled in the art to which it appertains to make and use the same.

The invention relates to improved means for adjusting and controlling casement windows, doors and the like and the object of the invention is to provide means for automatically retaining the window sash or door to which the adjuster is connected at any desired open position or when the same is in its closed position.

20 A further object of the invention is to provide a simple, durable and efficient device of this character which may be readily installed or removed and one which will be comparatively inexpensive to manufacture thereby rendering the same commercially desirable.

With the above and other objects in view the invention consists of the novel features of construction, combination, formation and arrangement of parts as will be hereinafter more fully described and particularly pointed out in the appended claims.

In the accompanying drawings there has been shown the simple and preferred forms of the invention it being evident, however, that no limitation is necessarily made to the precise structural details therein exhibited but the right is reserved to any changes, alterations, or modifications to which recourse may be had to come within the scope of the invention without departing from the spirit thereof or sacrificing the efficiency of the same.

In the drawings:

45 Figure 1 is a plan view embodying the invention showing the same when the window sash to which it is applied is opened and also showing the same in dotted lines when the window sash to which it is applied is in its closed position;

Fig. 2 is a detail section taken on the line 2—2 of Fig. 1;

Fig. 3 is a detail section;

Fig. 4 is a view similar to Fig. 1 illustrat-

ing a slight modified form of the invention; 55 and,

Fig. 5 is a detail cross section through the arms when closed together.

Referring now more particularly to the drawings wherein like and corresponding 60 parts are designated by similar reference characters throughout the several views the numeral 1 indicates a window casing shown by a fragmentary representation having a window sill 2 and a swinging casement window sash 3. The adjuster forming the subject matter of the present invention comprises a pair of companion arms indicated by the numerals 4 and 5 respectively which are pivotally connected together at one end 65 and the opposite ends of the arms being connected to the window casing and casement window respectively. These arms are preferably stamped from sheet metal as shown having their lower adjacent faces flat and 70 adapted to lie parallel to each other and extending longitudinally through the entire length of each arm is a reinforcing bead. One end of the arm 5 is pivotally connected as at 6 to a bearing bracket 7 permanently 75 connected to the sash.

One end of the arm 4 is pivotally connected to circular block 8 which is adapted to be detachably mounted within a socket bearing plate 9. This bearing plate is fixed 85 to the sill of the window casing by means of the set screws 10 and has its medial portion raised to form a socket 11. The socket 11 is provided with an opening through which may be inserted the block 8 and to 90 retain this block within the socket 11 a lug 12 is formed integral with the periphery of the block so that it will travel beneath the flange 13 formed with the socket 11 thereby 95 permitting the block 8 to rotate within the socket but at the same time prevent its withdrawal. When it is desired to disconnect the arm 4 from the window casing I provide within the flange 13 a notch 14 so that when the arm is turned at right angles to the sill of the window casing the lug 12 will register with the notch and by pulling 100 outwardly on the block 8 the same may be removed from the socket. To retain the sash in its adjusted position I provide a frictional connection between the connecting ends of the arms 4 and 5. From Fig. 1 it will be noted that the connecting ends of

the arms 4 and 5 are of a circular contour having recesses formed within their outer faces in which are arranged a plurality of superimposed plates of non-corrodible metal which plates and arms are connected by means of the rivet 15. The arms 4 and 5 are preferably made of steel and the plates resting thereon are made preferably of copper and steel so that by two different metals 10 rubbing against each other a frictional connection is provided. The plates 16 are preferably made of copper and the intermediate plates 17 are preferably made of steel so that there will be layers of different contacting metals. The adjacent faces of the enlarged circular ends of the arms 4 and 5 are provided with annular recesses in which are arranged copper rings 18 and interposed between these rings is an annular 20 steel strand of metal 19. The connection between the arms 4 and 5 provides means for increasing friction so that the window sash will be retained in its adjusted position. The rings 18 and 19 providing the frictional connection between the adjacent faces at the connection between the arms 4 and 5 and the plates arranged upon the outer faces of the arms at the connection provide frictional connections between the arms and the 25 heads of the connecting rivet 15. By providing a plurality of superimposed plates 16 and 17 of different metals for forming the frictional connection should any one of the plates adhere to the arms 4 or 5 or to any 30 of the other adjacent plates the remaining plates which are free to turn upon each other will retain this frictional connection and the purpose of the connection will not be impaired.

35 40 From the foregoing it is obvious that the adjuster will permit the radial opening and closing of a casement window sash or door to which it may be applied and it will brace the same to prevent rattling by the wind 45 whether opened or closed and at the same time firmly holding the same in any position to which it may be swung upon its hinges without any occasion for special manipulation and permitting the door or window sash to which it is applied to open 50 clear. This frictional resistance between the companion arms 4 and 5 is not enough to cause annoyance in opening and closing the windows.

55 55 In Figs. 4 and 5 of the drawings I have illustrated a slightly modified form of the invention wherein the adjuster may be also used as a locking device for locking the sash when it is closed. In Fig. 4 I have shown 60 the device applied to the sash and window casing indicated by the numerals 2 and 3 respectively and the adjuster is of the same construction as the one shown in Figs. 1 and 3 of the drawings, but I have added to each 65 of the arms 4 and 5 thereof the projecting

70 lugs 20 and 21 whereby the arms will be locked together as will be later described. It will also be noted that in this figure of the drawings the bearing plate 9 is connected adjacent to the medial portion of the window casing, but the pivotal connection between the arms 4 and 5 extends toward one side of the casing or adjacent the pivotal connection between the window casing and the sash. When the sash is closed the arms 4 and 5 lie 75 parallel with each other and the pivotal connection between the outer end of the arms 4 and 5 on the sash and window casing respectively lie one above the other or in the same alinement and the arms assume the position as indicated in dotted lines as at A in Fig. 4 of the drawings. When the arms have assumed this position the lug 21 carried by the arm 5 extends over the edge of the arm 4 and likewise the lug 20 of the arm 4 80 extends over the edge of the arm 5 as better shown in Fig. 5 of the drawings. When the window sash is closed and the arms of the adjuster are in the position as shown in dotted lines as at A the window sash may be 85 readily opened and the lugs 20 and 21 will permit the respective arms of the adjuster to pass but when the arms have been swung around their outer pivot connections and have assumed the position as shown at B in 90 dotted lines of Fig. 4 of the drawings the window sash will be locked and held against opening by means of the lugs 20 and 21.

Having thus fully described my invention, what I claim as new and desire to set 100 secure by Letters Patent is:

1. A casement window adjuster comprising a pair of companion arms, means for pivotally connecting one end of said arms together the adjacent faces of said arms having annular grooves formed therein, resistance members arranged within said grooves, and resistance plates arranged upon the outer faces of said arms around said pivotal connection. 105

2. A casement window adjuster comprising a pair of companion arms, a pivoted connection between one end of said arms, annular plates arranged concentric with said pivoted connection and resting adjacent to 110 the inner faces of said arms, a ring interposed between said plates, and a plurality of superimposed plates arranged upon the outer faces of said arms and concentric with said pivoted connection. 115

3. The combination with a window casing and a window sash pivotally mounted therein, an arm pivotally and detachably connected to the window casing adjacent its medial portion, a companion arm pivotally connected at one end to the window sash, means for frictionally connecting the inner ends of the arms together, a lug projecting from one edge of the companion arm and adapted to engage over the other arm when the window 120 125 130

sash is closed within the window casing, the other arm having a depending lug projecting from one edge thereof at the opposite side of said arm to which the lug is projected from the companion arm and this lug is adapted to engage over the companion arm when the window sash is closed, the pivoted connections between said arms and the window casing and window sash respectively adapted to lie concentric when the window sash is closed whereby when said

arms are swung upon the pivoted connections to the window casing and window sash respectively so as to lie at a straight angle from their normal position when the window sash is closed the arms will be locked together and the window sash held against opening. 15

In witness whereof I have hereunto set my hand.

JOSEPH GEORGE HUOT.
